INVENTOR.

Ernest B. Crocker,
By his Atty
Henry C. Williams.

UNITED STATES PATENT OFFICE.

ERNEST B. CROCKER, OF BOSTON, MASSACHUSETTS.

DESIGN FOR A GUIDE FOR ROLLER WINDOW-SCREENS.

SPECIFICATION forming part of Design No. 33,945, dated January 22, 1901.

Application filed December 27, 1900. Serial No. 41,293. Term of patent 14 years.

To all whom it may concern:

Be it known that I, ERNEST B. CROCKER, a citizen of the United States, residing at Boston, in the county of Suffolk and State of Massachusetts, have invented a new and original Design for Guides for Roller Window-Screens, of which the following is a specification, reference being had to the accompanying drawings, forming part thereof.

Figure 1 is a perspective view of a guide for roller window-screens, showing my new design. Fig. 2 is a side elevation of the same. Fig. 3 is an elevation of the side opposite to that shown in Fig. 1.

Similar letters of reference indicate corresponding parts.

As shown in the drawings, the leading or material feature of my design consists of the central straight longitudinal narrow surface A, the parallel folds B C, extending from said surface at right angles, and the parallel folds D E, extending from the folds B C, respectively, at right angles. The fold E is shorter at its lower end than the other folds and is

formed up at that end into the substantially 25 tubular roll E'. The fold B is provided near its lower and upper ends, respectively, with the central round holes B' and B'', the latter being smaller in diameter than the former, and the fold C is provided near its lower and 30 upper ends, respectively, with the central round holes C' and C'', the hole C' being opposite, concentric with, and smaller in diameter than the hole B', and the hole C'' being opposite, concentric with, and smaller in diameter than the hole B. 35

Having described my invention, what I claim as new, and desire to secure by Letters Patent, is—

The design for a guide for roller window- 40 screens, as herein shown and described.

In testimony whereof I have signed my name to this specification in the presence of two subscribing witnesses.

ERNEST B. CROCKER.

Witnesses:
